DESIGN.

D. McNAIR.

CARPET.

No. 15,635.

Patented Dec. 23, 1884.

UNITED STATES PATENT OFFICE.

DAVID McNAIR, OF BOSTON, MASSACHUSETTS, ASSIGNOR TO THE ROXBURY CARPET COMPANY, OF SAME PLACE.

DESIGN FOR A CARPET.

SPECIFICATION forming part of Design No. 15,635, dated December 23, 1884.

Application filed November 12, 1884. Term of patent 3½ years.

To all whom it may concern:

Be it known that I, DAVID McNAIR, of Boston, in the county of Suffolk and State of Massachusetts, have invented a new and original 5 Design for Carpets, of which the following is a specification.

The nature of my design is fully shown in the accompanying photographic illustration.

The design is composed of the floral and 10 foliage ornamentation and mottled ground-work shown.

I claim—

The design for a carpet, substantially as shown and described.

In testimony whereof I have signed my name 15 to this specification, in the presence of two subscribing witnesses, this 8th day of November, 1884.

DAVID McNAIR.
